DESIGN FOR A COMBINED FOUNTAIN PEN AND CHECK PROTECTOR OR SIMILAR ARTICLE

Charles J. MacNally, Jamaica, N. Y.

Application October 19, 1937, Serial No. 72,311

Term of patent 14 years

To all whom it may concern:

Be it known that I, Charles J. MacNally, residing at Jamaica, Long Island, in the county of Queens and State of New York, have invented a new, original, and ornamental Design for a Combined Fountain Pen and Check Protector or Similar Article, of which the following is a specification, reference being had to the accompanying drawing, forming part thereof.

fountain pen and check protector showing my new design.

I claim:

The ornamental design for a combined fountain pen and check protector or similar article, substantially as shown and described.

CHARLES J. MACNALLY.
